UNITED STATES PATENT OFFICE.

MOSES MOSLER, OF CINCINNATI, AND CARL BARTELS, OF HAMILTON, OHIO, ASSIGNORS
TO THE MOSLER SAFE COMPANY, OF NEW YORK, N. Y.

SAFE CONSTRUCTION.

Specification of Letters Patent.

Patented May 25, 1915.

1,140,524.

Application filed January 2, 1915. Serial No. 72.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safe Construction, of which the following is a specification.

10 This invention, pertaining to safe construction, relates to the arrangement of an auxiliary door carried by the main door and adapted to make a special closure with the inner compartment of the safe, the auxiliary door opening with the main door or remaining in closed condition while the main door is open, as desired.

The invention will be readily understood from the following description taken in connection with the accompanying drawings in which:—

Figure 1 is a front elevation of a safe exemplifying our invention, a lower portion of the main door being broken away to expose the auxiliary door in its rear, while an upper portion of both doors is broken away to expose the jamb construction pertaining to both doors: Fig. 2 a front elevation of the auxiliary door: Fig. 3 a plan of the auxiliary door, in conjunction with the coupling-spurs carried by the main door, these spurs appearing in horizontal section in the plane of line *e* of Fig. 8: Fig. 4 a vertical section of the front portion of the safe in the plane of line *b* of Figs. 1, 2, 3, 5, 6 and 7: Fig. 5 a vertical section of the main door clutch in the plane of line *c* of Figs. 4 and 7: Fig. 6 a front elevation of portions of the locking mechanism, the main door clutch appearing in vertical section in the plane of line *d* of Figs. 4 and 7: Fig. 7 a plan of portions of the locking mechanism, the plates of the doors appearing in horizontal section in the plane of line *a* of Figs. 1, 2, 4, 5 and 6: Fig. 8 a perspective rear view of the upper portion of the main door in conjunction with one of the locking bars of the auxiliary door moved away from the main door: Fig. 9 a diagrammatic front elevation of a portion of the locking-dog in conjunction

with one of the tumblers of the combination lock: and Fig. 10 a vertical section of a lower portion of the doors and inner safe compartment, in the plane of line *f* of Figs. 1, 2 and 3.

55

A diversity of scales is employed in the drawings.

In the drawings:—1, indicates the front of the safe: 2, the stepped door-jamb thereof: 3, the inner compartment of the safe, the same to be formed in water-tight manner, as of metal with welded or brazed seams: 4, the rear portion of the door-jamb, the same to be firmly secured to the front portion of the walls of the inner compartment 65 3: 5, packing, of rubber or other suitable material, extending around within the door-jamb and exterior to the front portions of the walls of the inner compartment 3, which portions extend forwardly beyond the jamb- 70 portions 4 to which they are secured: 6, teeth projecting inwardly, at spaced intervals, from a rear portion of the door-jamb forward of the front edges of the walls of the inner compartment 3: 7, the main door, 75 considered as a whole, this door fitting the steps of the jamb in the usual manner: 8, the front plate of the main door: 9, a back or inner plate of the main door, forming a rigid part thereof and designed to carry 80 such locking mechanism as pertains to the main door: 10, the steps of the margin of the main door, fitting into the steps of the jamb, as usual: 11, the exterior handle for operating the locking bolts of the main 85 door: 12, the combination lock, considered as a whole: 13, spaces in the door and safe walls which may be provided to receive the usual fire-proof filling: 14, the bolts of the main door: and 15, the carrying-bar for 90 these bolts.

All of the parts of the main door including its bolts and bolt-throwing mechanism and locking mechanism, may be constructed in any usual or suitable manner. As thus 95 far considered the main door would furnish the usual fire-proof protection but, as is well understood, the steps of these doors cannot fit with tightness within the steps of the jamb, the consequence being that, in 100

case of flooding, water can get access to the interior compartment of the safe. In case the door is provided with packing to secure water-tightness, the water-tightness becomes lost when the main door becomes warped by the falling of the safe or by the action of water upon it while heated. In the present invention the water-tightness is secured by means of an auxiliary door co-operating with the front of the inner compartment and performing its functions independent of the main door.

Proceeding with the drawings:—16, indicates a plate seating against the front of the inner compartment 3 and forming the auxiliary door: 17, bolt-bars fitted to slide on the front face of the auxiliary door, there being one of these bolt-bars at each edge of the auxiliary door: 18, teeth projecting outwardly from the edges of these bars, these teeth being adapted, while the door is being closed, to pass in between jamb-teeth 6 and take position to the rear of the jamb-teeth and then, when the bolt-bars are shifted endwise, to pass behind the jamb-teeth and wedge the auxiliary door tightly against the front of the inner compartment 3, the co-operating faces of teeth 18 and the jamb-teeth being beveled to produce this wedging action as the bolt-bars are moved: 19, levers pivoted upon the front face of the auxiliary door and having their outer ends in engagement with bolt-bars 17, so that the oscillation of the levers will shift 35 the bolt-bars endwise to locking or unlocking position: 20, a pinion journaled on the front face of the auxiliary door and having its teeth engaging teeth on the inner ends of levers 19, so that the turning of the pinion will oscillate all of the levers simultaneously: 21, a clutch-member formed on the front face of the pinion: 22, bellcranks pivoted to the auxiliary door and connecting the contiguous ends of bolt-bars 17: 23, 40 a rearwardly presenting hook carried by the upper inner portion of the main door: 24, a forwardly presenting hook carried by the front face of the auxiliary door and adapted, when the two doors are in association, to engage over hook 23 of the main door: 25, a spindle journaled in the main door in axial alinement with pinion 20: 26, a clutch-member carried by the rear end of spindle 25 and adapted, when the two 45 doors are in association, to engage with clutch-member 21 carried by the auxiliary door: 27, a handle, exterior to the main door, to serve in turning the spindle 25: 28, a packing carried by a groove in the 50 rear face of auxiliary door 16, near its edge, and adapted to engage with the forward edges of the walls of inner compartment 3: 29, spurs projecting down from the inner upper portion of the main door 30, hooks

carried at the front face of the upper one 65 of bolt-bars 17 and adapted, when that bolt-bar is shifted to the unlocking position, to engage behind spurs 29: 31, a notch in the inner edge of one of the bolt-bars 17 of the auxiliary door, the illustration showing this 70 notch as being in the lower one of the bolt-bars: 32, a vertically sliding dog carried by the auxiliary door and having a portion adapted, as the dog moves downwardly, to engage in notch 31 and prevent the endwise shifting of the bolt-bar provided with that notch: 33, a toe on the outer end of dog 32 and adapted to ride on one of the bevels of the stepped door-jamb and hold the dog up to inactive position when the 80 doors are in closed position in the door-jamb: 34, a pivoted dog-lever carried by the main door and having an end adapted to engage in notch 43 of door-clutch 26 when the pinion is in angular position corresponding with the locked condition of the auxiliary door: 35, a prong carried by dog-lever 34 and adapted to enter the releasing notches of the tumblers of the combination lock; 36, a tail-piece extended inwardly 90 from the carrying-bar 15 of the bolts of the main door: 37, an incline on this tail-piece engaging an incline on that end of lever 34 which carries prong 35: 38, a peripheral notch in clutch-member 26 of the 95 main door: 39, a second similar notch in this clutch-member: 40, a vertically sliding detent carried by the rear portion of the main door near and radial to clutch-member 26: 41, a tooth on the end of detent 40 100 adapted to engage notch 39 in one position of the auxiliary bolt-work and to engage notch 38 in another position of the auxiliary bolt-work: 42, an incline on tail-piece 36 of the carrying-bar of the bolts of the 105 main door, adapted to co-operate with an incline on detent 40 and move the detent toward clutch-member 26 when the carrying-bar is retracted: and 43, the notch of the main door clutch which is engaged by 110 one end of dog-lever 34.

All of the figures of the drawings with the exception of Fig. 8, assume both doors as being closed and bolted and that the combination lock has been set up so as to permit of 115 the unbolting of the doors.

Assume, now, that it is desired to open the safe completely. Handle 27 is to be turned, with the sun, the setting up of the combination lock permitting this, and the turning of 120 the handle causes pinion 20 to move bolt-bars 17 in the direction of the arrows *g* thus releasing their teeth 18 from the teeth 6 of the jamb. The auxiliary door is now unbolted from the jamb, and it is to be observed that the bolt-bars 17 will be moved 125 simultaneously by the four levers 19 and that they would be moved simultaneously in the

absence of three of these levers, by reason of the presence of the bellcranks 22. Now, looking at Fig. 6, and understanding that the auxiliary door has been unbolted from the jamb, handle 11 is operated and, through the usual mechanism, withdraws main door bolts 14. This action results in incline 42 lifting detent 40 and causing detent tooth 41 to enter notch 38 in the main door clutch, 10 this notch having been angularly advanced by the turning of the handle 27 which released the auxiliary door bolts. Incline 37 on the tail-piece of the carrying-bar is not essential but it serves to insure the completion of the movement of dog-lever 34 in disengagement from notch 43. This unbolting movement of bolt-bars 17 has caused hooks 30 on one of these bolt-bars to engage in front of spurs 29 carried by the main door, 20 the result being that the auxiliary door is locked to the main door and cannot be unlocked therefrom until the bolts of the auxiliary door are again thrown. Both doors are now unbolted from the jamb and may be 25 opened, the auxiliary door coming with and forming virtually a part of the main door. As the compound door opens, the toe of dog 32 rides off of the bevel of the jamb and permits the dog to drop into notch 31. If, now, 30 a meddling attempt be made to operate handle 27 and throw the bolts of the auxiliary door it cannot be done on account of the retaining action of dog 32.

When the safe is to be closed, the compound door is pushed shut and the main door-bolts thrown by means of handle 11 and, if desired, the combination lock is thrown. This leaves the main door locked in the jamb but has no effect in moving the auxiliary door against the inner compartment, and it is desirable, for the sake of conserving the life of the packing, not to put this packing into service except when the auxiliary door is to be put into its special 45 service. When the safe, under these closed conditions, is to be opened, it is only necessary to set up the combination lock and to draw the main door bolts.

Assume, now, that it be desired not only 50 to close and bolt the main door but to close and bolt the auxiliary door. The compound door is to be closed, as in the case just mentioned, and the main door bolts thrown. The closing of the compound door has released dog 32 from notch 31, freeing the 55 bolts of the auxiliary door. If an attempt be made to throw the bolts of the auxiliary door before the main door bolts have been thrown, the attempt will be defeated by the 60 engagement of detent tooth 41 in notch 38 of the main door clutch. But, the main door bolts having been thrown, handle 27 may then be manipulated to throw the auxiliary bolts and cause the auxiliary door to

move a trifle away from the main door and 65 go into intimate water-tight contact with the inner compartment of the safe. The throwing of the combination lock will then lock the compound door.

We have thus far explained the unbolting 70 and opening of the compound door as a unit; the closing of the compound door and the bolting of the main door only; and the closing of the compound door and the bolting of 75 both its components.

Assume, now, that it be desired to open the main door and leave the auxiliary door bolted to place. The combination lock having been set up, the main door bolts may be drawn and the main door opened, leaving 80 the auxiliary door sealed against the front of the inner compartment of the safe and firmly bolted, clutch member 26 of the main door separating away from clutch-member 21 of the auxiliary door. The main door 85 having thus been opened away from the auxiliary door gives access to the combination lock and to the general bolting mechanism.

When the main door bolts were drawn, 90 preparatory to the opening of the main door without opening the auxiliary door, detent tooth 41 entered notch 39 which insures that the angular position of the main door-clutch shall be such as to permit the clutch-members to reengage when the main door is again closed against the auxiliary door.

We have chosen to illustrate our invention in a safe of square door fireproof type, the auxiliary door having its bolting mechanism of sliding toothed bar type, but it is to be understood that the particular construction set forth is but a single exemplification of our invention which may be 100 realized in numerous modifications.

We have simply sought to explain the principle of our invention and to set forth the best form in which we at present contemplate embodying that invention.

We claim:—

1. In a safe door, the combination with a main door, bolting and locking mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front 115 of the inner compartment, and actuating mechanism carried by the main door to serve in operating the bolting mechanism of the auxiliary door, of separable clutch-members carried by said actuating mechanism and the bolting mechanism of the auxiliary door, whereby the bolts of the auxiliary door may be thrown and drawn while the 120
2. In a safe door, the combination with a main door, bolting and locking mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front 125 of the inner compartment, and actuating mechanism carried by the main door to serve in operating the bolting mechanism of the auxiliary door, of separable clutch-members carried by said actuating mechanism and the bolting mechanism of the auxiliary door, whereby the bolts of the auxiliary door may be thrown and drawn while the

- two doors are in association and whereby said actuating mechanism may move with the main door away from the auxiliary door so as to leave the auxiliary door bolted while the main door is open, substantially as set forth.
2. In a safe door, the combination with a main door, bolting and locking mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front of the inner compartment, and actuating mechanism carried by the main door to serve in operating the bolting mechanism of the auxiliary door, of separable clutch-members carried by said actuating mechanism and the bolting mechanism of the auxiliary door, and a dog carried by the auxiliary door and actuated by contact with the surface of the door-jamb and adapted to prevent the releasing movement of the bolting mechanism of the auxiliary door except when the auxiliary door is out of the door-jamb, whereby the bolts of the auxiliary door may be thrown and drawn while the two doors are in association and whereby said actuating mechanism may move with the main door away from the auxiliary door so as to leave the auxiliary door bolted while the main door is open and whereby the bolts of the auxiliary door may not be drawn while the main door is open and the auxiliary door closed, substantially as set forth.
3. In a safe door, the combination with a main door, bolting and locking mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front of the inner compartment, and actuating mechanism carried by the main door to serve in operating the bolting mechanism of the auxiliary door, of separable clutch-members carried by said actuating mechanism and the bolting mechanism of the auxiliary door, and coöperating hooking members carried by the main door and the auxiliary door and adapted to engage with each other when the bolts of the auxiliary door are drawn and to disengage from each other when they are thrown, whereby the bolts of the auxiliary door may be thrown and drawn while the two doors are in association and whereby said actuating mechanism may move with the main door away from the auxiliary door so as to leave the auxiliary door bolted while the main door is open, and whereby the auxiliary door when unbolted becomes hooked to the main door, substantially as set forth.
4. In a safe door, the combination with a main door, bolting mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front of the inner compartment, and actuating mechanism carried by the main door to serve in operating the bolting mechanism of the auxiliary door, of separable clutch-members carried by said actuating mechanism and the bolting mechanism of the auxiliary door, and locking mechanism carried by the main door and connected with the bolting mechanism thereof and said actuating mechanism, whereby the bolts of the auxiliary door may be thrown and drawn while the two doors are in association and whereby

leave the auxiliary door bolted while the main door is open, and whereby the main door supports the auxiliary door when the two doors are in association, substantially as set forth.

4. In a safe door, the combination with a main door, bolting and locking mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front of the inner compartment, operating mechanism connecting the bolting mechanism of the main door and the bolting mechanism of the auxiliary door and serving to lock the auxiliary bolting mechanism in drawn position so long as the bolting mechanism of the main door is in drawn position, and actuating mechanism carried by the main door to serve in operating the bolting mechanism of the auxiliary door, of separable clutch-members carried by said actuating mechanism and the bolting mechanism of the auxiliary door, and coöperating hooking members carried by the main door and the auxiliary door and adapted to engage with each other when the bolts of the auxiliary door are drawn and to disengage from each other when they are thrown, whereby the bolts of the auxiliary door may be thrown and drawn while the two doors are in association and whereby said actuating mechanism may move with the main door away from the auxiliary door so as to leave the auxiliary door bolted while the main door is open, and whereby the auxiliary door when unbolted becomes hooked to the main door, substantially as set forth.

5. In a safe door, the combination with a main door, bolting mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front of the inner compartment, and actuating mechanism carried by the main door to serve in operating the bolting mechanism of the auxiliary door, of separable clutch-members carried by said actuating mechanism and the bolting mechanism of the auxiliary door, and locking mechanism carried by the main door and connected with the bolting mechanism thereof and said actuating mechanism, whereby the bolts of the auxiliary door may be thrown and drawn while the two doors are in association and whereby

5 said actuating mechanism may move with the main door away from the auxiliary door so as to leave the auxiliary door bolted while the main door is open and whereby the bolts of both doors may be locked, substantially as set forth.

6. In a safe door, the combination with a main door, bolting and locking mechanism carried thereby, a water-tight inner compartment, an auxiliary door carried by the main door but entirely separable therefrom and adapted to move away from the main door and close against the front of the inner compartment, bolting mechanism carried by the auxiliary door and adapted to force the auxiliary door to closure against the front of the inner compartment, and actuating mechanism carried by the main door to serve in operating the bolting mechanism of the auxiliary door, of separable clutch-members carried by said actuating mechanism and the bolting mechanism of the auxiliary door, a detent carried by the main door and adapted to detain said actuating mechanism in the position corresponding with either the thrown or drawn condition of the bolting mechanism of the auxiliary door, and connections between the bolting mechanism of the main door and said detent to cause the drawing of the bolts of the main door to detain such actuating mechanism in either of said two positions, whereby the bolts of the auxiliary door may be thrown and drawn while the two doors are in association and whereby said actuating mechanism may move with the main door away from the auxiliary door so as to leave the auxiliary door bolted while the main door is open, and whereby the actuating mechanism may be locked in either thrown or drawn position when the main bolts are drawn, substantially as set forth.

7. A safe comprising, a doorjamb having its rear portion inwardly offset from its forward portions, a watertight inner compartment having its forward portion secured to the rear portion of the jamb and projecting forwardly of the offset portion so as to form a groove extending entirely around the front portion of the compartment between it and the portion of the jamb immediately forward of said offset, packing disposed in the groove thus formed, and a door adapted to close against such packing, combined substantially as set forth.

8. A safe comprising, a doorjamb having its rear portion inwardly offset from its forward portions, a watertight inner compartment having its forward portion secured to the rear portion of the jamb and projecting forwardly of the offset portion so as to form a groove extending entirely around the front portion of the compartment between it and the portion of the jamb immediately

forward of said offset, packing disposed in the groove thus formed, a door adapted to coöperate with the doorjamb and with the forward portion of said compartment and having its margin extending outwardly over said groove and adapted to engage said packing, the rear face of the door being provided with a continuous groove at the point of engagement of the door with the inner portion of the compartment, and packing disposed in the groove of the door and adapted to engage the front portion of the compartment and coöperate with the first-mentioned packing, combined substantially as set forth.

9. A safe door comprising, a door-jamb with tapering steps, a main door adapted to close into said jamb, a water-tight inner compartment, an inner door carried by the main door but entirely separable therefrom and adapted to move from the main door and against the front of the water-tight compartment, mechanism accessible from the exterior of the main door and adapted to force the auxiliary door against the front of the inner compartment, and a separable coupling in said mechanism to permit the operation of that mechanism while the two doors are in association and still permit the opening of the main door while the auxiliary door remains closed, combined substantially as set forth.

10. A safe door comprising, a rectangular door-jamb provided with inwardly projecting teeth spaced apart from each other, a rectangular main door, bolting and locking mechanism carried thereby, a rectangular water-tight inner compartment, a rectangular auxiliary door carried by the main door and adapted to move away from the main door and close against the front of the inner compartment, sliding bolting bars carried at the margins of the auxiliary door, outwardly projecting teeth carried by said bars and adapted to enter between and then engage behind the teeth of the jamb, means connecting said bars to cause them to slide in unison, and actuating mechanism carried by the main door and adapted to slide said bars, combined substantially as set forth.

11. In a safe door, the combination of a main door, an auxiliary door connected therewith, sliding locking bars carried by the margins of the auxiliary door, teeth projecting outwardly from the bars and adapted to pass between and engage behind appropriate teeth projecting inwardly from the jamb into which the door is to close, a pinion carried loosely at the front of the auxiliary door, levers pivoted to the auxiliary door and having their outer ends in engagement with said bars and having their inner ends toothed and in engagement with said pinion, and mechanism connecting the

contiguous ends of the bars, and mechanism carried by the main door for turning said pinion, substantially as set forth.

12. A safe door comprising, a main door, bolting and locking mechanism connected therewith, an auxiliary door movable away from the main door, bolting mechanism carried by the auxiliary door, a pinion mounted on the auxiliary door and operatively connected with the bolting mechanism of the auxiliary door, a clutch carried by said pinion, a spindle mounted in the main door in

axial alinement with said pinion and accessible for rotation from the front of the main door, and a clutch carried by the rear end of 15 said spindle and adapted to engage the clutch of the pinion, combined substantially as set forth.
